DEVICE FOR THE NIGHTLY LIGHT BEACONING OF HIGH TENSION OVERHEAD CABLES

Joseph Béthenod and Daniel Kayser, Paris, France, assignors to Société Anonyme pour les Applications de l'Électricité et des Gaz Rares-Etablissements Claude-Paz & Silva, Paris, France

Application March 11, 1939, Serial No. 261,352
In Switzerland March 31, 1938

7 Claims. (Cl. 177—352)

This invention relates to a device for the nightly light-beaconing of overhead high tension cables, by means of luminescent electric discharge tubes.

This device utilizes the known method of feeding a luminescent tube, which consists in connecting one of the high tension cables to one of the electrodes of the said tube, the other electrode being connected to an insulated metallic (capacitative) element, the effect of which may be augmented by an auxiliary cable arranged parallel to and at a slight distance from the cable to be lighted.

According to the invention, the luminescent discharge tube is held in a preferably vertical position above the high tension cable by means of an insulating support attached to the said cable, while the metallic member forming the capacitative element is suspended from the insulating support below the said cable by means of at least one curved arm turning round the high tension cable. One electrode of the luminescent tube is connected to the said cable by means of a conductor preferably passing through the insulating support, the other electrode being connected to the metallic member by means of the curved arm or arms from which the said metallic element is suspended.

The vertical position of the luminescent discharge tube above the cable to be lighted is evidently very advantageous in that it ensures a satisfactory distribution of the light rays; it also prevents either the cable to be lighted or the various members which hold the luminescent tube in position or supply current to its electrodes from acting as screens.

Moreover, the metallic element suspended upon the insulating support of the luminescent discharge tube acts as a counterweight, and thus prevents angular displacement of the said tube and by making this of suitable size and shape it may at the same time be utilized for balancing the torque due to wind pressure upon the entire lighting installation.

The invention will be clearly understood from the accompanying drawing which illustrates an embodiment given by way of example.

Fig. 1 shows a plan view of the marker;

Fig. 2 is a sectional view of Fig. 1 with parts in elevation; and

Fig. 3 shows a modification of the invention.

In Figure 1 which is a view in perspective, 1 indicates one of the cables to be lighted. In accordance with the invention the socket 2 of the luminescent tube 3 which latter may for ex-

ample be in the form of a spiral, is held in position by means of an insulator 4 attached to the cable 1 by means of a two piece metallic sleeve 5 (or equivalent member). As regards the capacitative element 6 this is suspended from the socket 2 through the intermediary of two curved arms 7 which encircle the conductor 1 at a convenient distance.

As is known, this element serves the purpose of increasing the capacitative effect to earth of the electrode which is not connected to the conductor 1, and consequently of ensuring a better feeding of the luminescent tube. It is further known to augment this effect with advantage by means of an auxiliary conductor cable which is disposed parallel to and at a slight distance from the conductor 1. Such a conductor 8 is shown in Figure 3, and, in case said conductor is too long to be supported by the arms alone, its extremities 20 may be supported by insulators (not shown) suspended from the conductor 1. In any case the volume, weight and section of the element 6 may evidently be so chosen as to ensure perfect mechanical stability of the installation, taking into account the wind-pressure if any.

Figure 2 is a sectional view of certain details particularly of the electrical connections of the various members, on a plane vertical to that of the cable 1. The luminescent tube 3, protected by a transparent envelope 9, has one of its electrodes 10 connected to the element 6 through the intermediary of the annular socket 2 and the curved arms 7, while the electrode 11 is connected to the conductor 1 by means of a lead 12 passing through the insulator 4. Moreover, a stabilizing resistance 13 may be interposed in the said lead and may be located in a hollow space provided in the interior of the said insulator. As will be seen in the drawing, the insulator may also be extended upwardly by means of a hollow column 14 which serves the purpose of maintaining in position the luminescent tube which is wound in a spiral upon the said column. Replacement, if any, of the said luminescent tube is thus made very easy once the envelope 9 has been removed, an operation which may be facilitated by means of an attachment in the manner of a screw or bayonet socket 2.

It is evident that several alternatives of the preceding arrangements may be provided without thereby deviating from the invention as set forth in the appended claims.

What we claim is:

1. A marker for a high voltage overhead cable, comprising an insulator provided at its base with

a connector for securing said insulator to the cable and at its top with a rigidly depending bracket member extending about and below the cable, an electric discharge lamp on the top of the insulator, electrodes for said discharge lamp, said electrodes being connected to said connector and bracket member, respectively, and a capacitive counterweighting member connected to the lower end of said bracket member and adapted to hold the insulator and lamp assembly upright on the cable and to evolve a light energizing capacitive leak current from the cable through said lamp.

2. A marker for a high-voltage overhead cable, comprising a hollow insulator provided at its base with a connector for securing said insulator to the cable and at its top with a hollow insulating upright stem and a rigidly depending bracket member extending about and below the cable, an electric discharge tube of a generally vertical design, arranged about said stem, upper and lower electrodes for said tube, said upper electrode being connected to said connector through the hollow in said insulator and stem and the lower electrode being connected to said bracket member, and a capacitive counterweighting member connected to the lower end of said bracket member and adapted to hold the insulator and lamp assembly upright on the cable and to evolve a light energizing capacitive leak current from the cable through said lamp.

3. A marker for a high-voltage overhead cable, comprising a hollow insulator provided at its base with a connector for securing said insulator to the cable, a bracket member formed at one end with a sleeve portion secured to the top of the insulator and depending from said portion to extend about and below the cable, an electric discharge lamp on the top of the insulator, electrodes for said discharge lamp, one of said electrodes being connected to said connector and the other of said electrodes being connected to the sleeve portion, a glass bell housing for said lamp, having its lower open end secured to said sleeve portion, and a capacitive counterweighting member connected to the lower end of said bracket member and adapted to hold the insulator and lamp assembly upright on the cable and to evolve a light energizing capacitive leak current from the cable through said lamp.

4. A marker for a high-voltage overhead cable, comprising an electric lighting unit, means for securing said lighting unit to said cable and at one side thereof, a capacitative element positioned on the opposite side of the cable from said lighting unit and constructed to evolve a light-energizing capacitative leak current from the cable through the unit, terminals for said lighting unit,

means connecting one of said terminals to the cable and the other of said terminals to the capacitative element, said capacitative element being of such weight that it will serve as a counterweight for said lighting unit to maintain it in an upright position.

5. A marker for a high-voltage overhead cable, comprising an electric lighting unit, means for supporting said lighting unit in an upright position above said cable, a capacitative element suspended below the cable and constructed to evolve a light-energizing capacitative leak current from the cable through the unit, terminals for said lighting unit, means connecting one of said terminals to the cable and the other of said terminals to the capacitative element, said capacitative element being of such weight that it will serve as a counterweight for said lighting unit to maintain it in an upright position.

6. A marker for a high-voltage overhead cable, comprising an electric lighting unit, means for supporting said lighting unit above said cable, a capacitative element suspended below the cable and adapted to evolve a light-energizing capacitative leak current from the cable through the unit, means on said capacitative element for securing an auxiliary capacitative member thereto, terminals for said lighting unit, means connecting one of said terminals to the cable and the other of said terminals to the capacitative element, said capacitative element being of such weight that it will serve as a counterweight for said lighting unit to maintain it in an upright position.

7. A marker for a high-voltage overhead cable, comprising a hollow insulator provided at its base with a connector for securing said insulator to the cable and provided at its top with a hollow insulating upright stem, a rigidly dependent bracket member extending about and below the cable, an electric discharge tube of generally vertical design arranged about said stem, upper and lower electrodes for said tube, said upper electrode being connected to said connector through the hollow in said insulator and stem, a stabilizing resistance interposed between said upper electrode and said connector and positioned in the hollow of said insulator, the lower electrode of said tube being connected to said bracket member, and a capacitative counterweighting member connected to the lower end of said bracket member and adapted to hold the insulator and lamp assembly upright on the cable and to evolve a light-energizing capacitative leak current from the cable through said lamp.
